(57) **CLAIM**

The ornamental design for a semiconductor testing machine, as shown.

DESCRIPTION

FIG. 1 is a front, top and right side perspective view of a semiconductor testing machine showing our new design; FIG. 2 is a front elevational view thereof; FIG. 3 is a rear elevational view thereof; FIG. 4 is a top plan view thereof; FIG. 5 is a bottom plan view thereof; FIG. 6 is a right side elevational view thereof; and, FIG. 7 is a left side elevational view thereof.
